Inventor:
George A. Knapp

By Force & Bain & Hinckle Atty.

UNITED STATES PATENT OFFICE.

GEORGE A. KNAPP, OF CHICAGO, ILLINOIS, ASSIGNOR TO KNAPP BROTHERS MANUFACTURING COMPANY, A CORPORATION OF ILLINOIS.

METALLIC BASEBOARD STRUCTURE.

Application filed June 23, 1921. Serial No. 479,735.

To all whom it may concern:

Be it known that I, GEORGE A. KNAPP, a citizen of the United States, residing at Chicago, in the county of Cook and State of Illinois, have invented certain new and useful Improvements in Metallic Baseboard Structures, of which the following is a specification.

The invention relates to improvements in metallic base board structures for buildings.

One of the objects of the invention is to generally improve devices of the character to be described.

Another object is to provide a composite metallic, wall base board which will automatically compensate for settling of the floor to prevent unsightly cracks or gaps between the floor and the joining part of the base board structure.

Another object is to provide a structure that may easily and quickly be applied; that is flexible to readily meet any inherent irregularities in the floor or the wall; that is inexpensive to manufacture, and that is capable of receiving a smooth, even finish resembling wood.

Other objects and advantages of the invention will readily appear.

In the drawings:—

Fig. 1 shows the structure as it appears at an inner corner and at an outer projecting corner of a room.

Fig. 2 is a section taken on line 2—2 of Fig. 1.

Fig. 3 is a section taken on line 3—3 of Fig. 2.

Fig. 4 is a section taken on line 4—4 of Fig. 2.

Fig. 5 is a section taken on line 5—5 of Fig. 2.

In all the views the same reference characters are employed to indicate similar parts.

In the drawings 10 represents the floor of a room and 11 and 12 represent fragments of a vertical wall at substantial right angles to each other.

The major member of the metal base board consists of the face plate 13 having an incurved top edge 14 with a salient edge 15 resting against the presented surface of the vertical wall. The lower edge of the face plate 13 is acutely inturned to provide a flange 16, the salient edge of which rests

against the surface of the wall 11 in the same vertical plane as the upper edge 15.

The face plate 13 is secured at intervals to the vertical wall by screws 17. The heads of these screws may be countersunk into the surface of the plate 13 by indenting the plate and the depressions due to this effect may be filled with any suitable plastic material, such as "smooth on," or the like, so that the surface will thereby be made uniform with the remaining front portion of the plate to receive a finish without exhibiting a blemish.

At the inner corner 18 of angularly related walls 11 and 12 there is a bracket or corner piece 19, angular in cross section and having ribs 20 to space it from the respective walls a suitable distance, so that the front of the plate 13 will be flush with the vertical inner surface of the corner piece. The members of the bracket 19 contain rabbits on each vertical edge to bring the plate 13 flush with the surface and screws 21 are inserted thru openings 22 made in these corner members to receive them. The corner brackets 19 join the plates 13 in vertical lines 23. The corner brackets 19 are also provided with a spacing hub 24 which may conveniently surround screws 21 to space the outer surface of the bracket the proper distance from the walls 11 and 12.

An outer corner bracket 25 is also provided with rabbits 33 to receive the vertical edges of the adjacent plate 13 and screws 27 pass thru the plate and thru perforations made in the flanges 33 of the bracket 25 into a suitable portion of the walls 11 and 12, as the case may be. These brackets also have spacing ribs 28.

When the plates 13 with the brackets 19 and 25 have been placed in contact with the vertical walls 11 and 12, in the manner described, the lower edges of the brackets and the plates do not extend quite to the floor line and, therefore, to complete the finish a curved cove strip 26 is placed below the face plate. The cove corner strip when extended along the floor line is preferably curved, as shown more clearly in Fig. 3, and is secured at intervals to the floor by means of screws 27. The lower edge 20 of the curved cove strip rests upon the floor 10, while the upper edge 29 overlaps the lower edge of the face plate 13 above the flange 16 to permit

relative vertical movement of the face plate 13 and the cove strip, so that intimate contact is always preserved between the members 13 and 26 should the floor settle below its normal location. The strip 26 is preferably curved or dished so as to overlie the objectionable angular corner between the vertical walls and the floor for the purpose of cleaning and for sanitary precaution.

10 A preferable cove corner member 30 is located below the member 19 and has an overlapping edge 31 in horizontal alignment with the upper edge 29 of the cove strip 26. The corner member 30 has a rabbet portion 15 33 underlying the cove strip 26 on both of its sides, so that the member 30 cannot be removed after the cove strips have been held in position by the screws 27. A similar bottom member 35 is placed at the bottom 20 of the bracket or corner member 25 and has an upper edge 36 in the horizontal alignment with the upper edges 29 and 31, respectively. The outer corner member 25 is held in place by screws 37 that pass thru 25 the face plate 13 into a suitable support 38 let into the plastered wall.

From the foregoing description it will be manifest that the members 13 and 26 may be separated to some extent and the overlapping 30 at their meeting edges will automatically compensate for any vertical relative displacement thereof.

The members 30 and 35 will move coextensively with the curved cove strip 26 and 35 as they overlap the relative members thereabove the same effect will be produced.

Having described my invention what I claim as new and desire to secure by Letters Patent, is:—

40 1. A metal base board comprising a face

plate for attachment to a vertical wall and a cove strip having its upper edge overlapping the lower edge of the plate and having its lower edge in contact with a floor to compensate for relative vertical displacement of the members and means independently of the plate to hold the strip in place.

2. A metal base board comprising a face plate for attachment to a vertical wall having its lower edge spaced away from the floor 50 and a cove strip having its upper edge overlapping the lower edge of the plate and having its lower edge in contact with a floor and secured to the floor to compensate for relative vertical displacement of the members. 55

3. A metal base board comprising a face plate for attachment to a vertical wall having its lower edge spaced away from the floor and a cove strip having its upper edge overlapping the lower edge of the plate and 60 having its lower edge in contact with a floor, secured to the floor, to compensate for relative vertical displacement of the members and two part overlapping corner bracket members at the ends of said plates to continue the respective surfaces around the corners. 65

4. A hollow metal base board comprising a face plate having an upper incurved horizontal edge and a lower turned flange with 70 its salient edge in the same vertical plane and a concave cove strip overlapping the lower edge of the plate and having its lower edge in contact with the floor and screws passing thru said strip and into the floor 75 at suitable intervals.

In testimony whereof I hereunto subscribed my name.

GEORGE A. KNAPP.
